(57) **CLAIM**

The ornamental design for a footbed for a shoe as shown and described.

DESCRIPTION

FIG. 1 is a front view of a first embodiment of a footbed for a shoe.

FIG. 2 is a rear view of the footbed of FIG. 1.

FIG. 3 is a top view of the footbed of FIG. 1.

FIG. 4 is a bottom of the footbed of FIG. 1.

FIG. 5 is an inside view of the footbed of FIG. 1.

FIG. 6 is an outside view of the footbed of FIG. 1.

FIG. 7 is a perspective view of the top, front and inside of the footbed of FIG. 1.

FIG. 8 is a perspective view of the top, rear and outside of the footbed of FIG. 1.

FIG. 9 is a perspective view of the top, rear and inside of the footbed of FIG. 1.

FIG. 10 is a perspective view of the top, front and outside of the footbed of FIG. 1.

FIG. 11 is a cross-sectional view of the footbed taken along line 11-11 of FIG. 3.

FIG. 12 is a cross-sectional view of the footbed taken along line 12-12 of FIG. 3.

FIG. 13 is a cross-sectional view of the footbed taken along line 13-13 of FIG. 3.

FIG. 14 is a front view of a second embodiment of a footbed for a shoe.

FIG. 15 is a rear view of the footbed of FIG. 14.

FIG. 16 is a top view of the footbed of FIG. 14.

FIG. 17 is a bottom of the footbed of FIG. 14.

FIG. 18 is an inside view of the footbed of FIG. 14.

FIG. 19 is an outside view of the footbed of FIG. 14.

FIG. 20 is a perspective view of the top, front and inside of the footbed of FIG. 14.

FIG. 21 is a perspective view of the top, rear and outside of the footbed of FIG. 14.

FIG. 22 is a perspective view of the top, rear and inside of the footbed of FIG. 14.

(Continued)

FIG. 23 is a perspective view of the top, front and outside of the footbed of FIG. 14.

FIG. 24 is a cross-sectional view of the footbed taken along line 24-24 of FIG. 16.

FIG. 25 is a cross-sectional view of the footbed taken along line 25-25 of FIG. 16; and,

FIG. 26 is a cross-sectional view of the footbed taken along line 26-26 of FIG. 16.
